UNITED STATES PATENT OFFICE.

GAETANO DI GIOVANNI, OF NEW YORK, N. Y.

WINDOW-CLEANER.

1,235,447.

Specification of Letters Patent. Patented July 31, 1917.

Application filed October 12, 1916. Serial No. 125,185.

To all whom it may concern:

Be it known that I, GAETANO DI GIOVANNI, a subject of the King of Italy, and a resident of the city of New York, borough of the Bronx, in the county of Bronx and State of New York, have invented a new and Improved Window-Cleaner, of which the following is a full, clear, and exact description.

This invention relates to cleaning devices 10 for windows and has for an object the provision of an improved simplified construction that is easily operated without the use of any appreciable energy.

Another object in view is to provide a 15 comparatively light but effective arrangement of pivotally mounted arms or bars and a cleaning member arranged at one end of one of the bars so that usually inaccessible parts may be reached.

20 A still further object of the invention is to provide a cleaning device for windows in which the cleaning head or squeegee may be used either interiorly or exteriorly of the window when the operator stands in approximately the same position.

In the accompanying drawing:

Figure 1 is a perspective view of an embodiment of the device, the same being shown in operation.

30 Fig. 2 is a side view of an embodiment of the invention.

Fig. 3 is a side view of the cleaning head disclosing certain features of the invention, the same being shown on an enlarged scale.

35 Fig. 4 is a side view of the pivotal connection and associated parts of the operating bars, the same disclosing certain features of the invention.

Fig. 5 is a longitudinal vertical section 40 through the structure shown in Fig. 4, the bars being shown spread apart.

Fig. 6 is a detail fragmentary sectional view showing a slightly modified form of arm connected to the cleaning head.

45 Referring to the accompanying drawing by numerals, 1 indicates a wall provided with a window 2 having the usual sashes and panes in the sashes. As shown in Fig. 1 a window cleaner 3 is provided which is supplied with a cleaning head 4 arranged on the supporting bar 5 which is pivotally connected by a pin 6 to the operating bar 7. The operating bar 7 may be collapsed and the head 4 moved for cleaning or wiping the 55 exterior of the window pane while the operator remains within.

The bars 5 and 7 are pivotally connected as above stated, the connection being through the fittings 8 and 9. The fitting 9 is provided with a cut or passageway 10 into which the tongue or reduced portion 11 of fitting 8 extends so that the pivotal pin 6 may extend therethrough and also through the fitting 9. Tongue 11 is provided with a spur 12 for receiving one end of a spring 65 13, while fitting 9 is provided with a spur 14 for receiving the opposite end of spring 13. This spring when in position continually tends to hold the bars 5 and 7 together as shown in Fig. 2. In order to assist this 70 action of spring 13 an auxiliary spring 15 may be provided if desired mounted on the pin 6 which projects beyond the fitting 9, the ends of the spring 15 being hooked or looped around the studs or pins 16. If it 75 should be found that the use of both springs produces too great a tension either of the springs may be removed, preferably spring 15.

At the end of the bar 5 opposite the fitting 8 is arranged the cleaning head or squeegee 4. This head is provided with a body 17 of wood or other suitable material, which body in turn is provided with a rubber covering member 18 at the upper edge 80 so as to wipe or clean the window as desired. Preferably, during the cleaning operation when the window is being washed a piece of cloth 19 is folded over body 17 and is held in position by spring clips 20 and 21 secured to a retaining band 22, which retaining band is clamped in any suitable manner to the bar 5. The bar 5 and also the bar 7 may be made from any suitable material, as for instance wood, as such material 95 is comparatively light and will produce a very light complete structure which may be readily operated as shown in Fig. 1. When it is desired to clean the interior part of the window the same may be readily done, 100 as well as cleaning the exterior. After the window has been washed, as for instance by using the cloth covering 19, said covering is removed and the window wiped dry by moving the rubber member 18 thereover in the 105 usual way that squeegees are now commonly operated.

In some instances it is desired to clean an extra large window or an extra small window and to accommodate the device readily 110 to windows of this character a slightly modified form of rod is secured to the head 4,

the same comprising a section 5' and a section 5''. The section 5' is connected with the head 4 while the section 5'' is connected to the bar 7 as in the preferred structure. 5 The section 5' extends into a metallic sleeve 23 and fits sufficiently tight to stay in any position in which it is placed. The sleeve 23 is provided with rings 24 and 25 surrounding the section 5' and secured thereto 10 if desired by staples or any other way preferred.

What I claim is:

1. A window cleaner comprising a pair of bars, each of said bars being provided with 15 a fitting at one end, one of said fittings being formed with a tongue and the other with a cut-out slot, said tongue fitting into said slot, means for pivotally connecting said fittings so that said tongue will be pivotally

mounted in said slot, a spring extending 20 through said slot, means for connecting the opposite ends of said spring to the respective fittings, and means forming a cleaning head secured to the free end of one of said bars. 25

2. A window cleaner, comprising a pair of bars, each of said bars being provided with a fitting at one end, one of said fittings being formed with a tongue and the other with a cut-out slot, said tongue fitting into said 30 slot, means for pivotally connecting said fittings so that said tongue will be pivotally mounted in said slot, a spring acting on said fittings to give said bars a tendency to remain in contact, and means forming a cleaning head secured to the free end of one of the bars. 35

GAETANO DI GIOVANNI.
